RIDING RING FOR ROTARY CYLINDERS

Charles H. Patten, Allentown, Pa., assignor to
Traylor Engineering & Manufacturing Company,
Allentown, Pa., a corporation of Delaware

Application May 21, 1947, Serial No. 749,613

1 Claim. (Cl. 308—204)

1 The present invention relates to riding rings for rotary cylinders.

Rotary cylinders, such as the shells of rotary kilns, coolers, driers and grinding mills, are provided with a plurality of riding rings which rotate in fixed bearing elements to thereby rotatably support the cylinders. It has heretofore been the practice to form each riding ring of one piece of material and apply the rings by sliding them endwise along the cylinders. As a result, initial application of a ring, as well as replacement, involves a considerable period of time and labor.

An important object of the present invention is to provide a riding ring formed in sections so that it more readily can be applied to a cylinder.

Other objects and advantages of the invention will be apparent from the following specification and accompanying drawings, wherein

Figure 1 is an end view of a ring, the view showing a cylinder in transverse section,

Figure 2 is a radial section on the angled line 2—2 of Figure 1,

Figure 3 is a fragmentary face view of the ring of Figures 1 and 2, i. e., a view looking toward the Figure 1 ring in a radial direction and from above Figure 1, and

Figure 4 is a sectional view on the angled line 4—4 of Figure 3.

This application is related to my copending application, Serial No. 83,492, filed March 25, 1949.

Referring to Figures 1 to 4, these figures disclose a cylinder 10 of a type employed in a calcining kiln or similar apparatus. This cylinder is provided with a number of riding rings generally designated by the numeral 30 and formed of two or more sections 31 and 32. The sections 31 and 32 are provided with complementary or interfitting hooks 33 and 34, respectively, at their adjoining ends. The ring sections are provided with side walls 35 and 36 having flanges 35a and 36a, respectively, at their inner edges.

Referring to Figure 3, it will be noted that the hook 33 comprises a shank 33a of less width than the body of section 31 and a head 33b. One side wall of the shank and head is simply a continuation of the side wall 35 of section 31. The other side wall 33c of the shank is at an obtuse angle to the side wall 35 and its inner end joins wall 33d which extends at right angles to the side walls of section 31. The side wall 33f of head 33b lies parallel to the shank wall 33c but is offset with respect to the latter wall so as to provide a detent surface 33g. The outer end wall 33h

of the head 33b is parallel to wall 33d. It will be understood that each of the walls 33d, 33g and 33h lie along radii of the ring.

As is indicated in Figure 2, the hook 33' at the opposite end of section 31 will be displaced and reversed with respect to the hook 33. Also, it will be clear from Figure 3 that the hooks at the ends of the section 32 are identical and respectively complementary to the hooks on the section 31.

The manner in which the hooks of the sections 31 and 32 interengage will be clear from Figure 3. After the hooks have been assembled, they will be secured together by rivets 37 extending through aligned apertures in the hooks.

The ring 30 formed by the sections 31 and 32 may be secured to the cylinder 10 in the manner illustrated in Figure 2 of my above mentioned copending application, Serial No. 83,492, or it may be secured to the cylinder in the manner illustrated in Figure 2 and hereinafter described.

Referring to Figure 2, wedge shaped shims 38 of relatively short width circumferentially of the ring are driven beneath the oppositely inclined under surfaces 39 and 40 of the ring. The arcuate strips 41 are welded to the outer ends of the shims as indicated in Figure 2. If desired, the bar 41 at one side may be provided with inclined teeth as described in the application of Richard Bernhard for Riding Ring Mounting for Rotary Cylinders, Serial Number 693,599, filed August 28, 1946, now Patent Number 2,449,198, issued September 14, 1948, these teeth cooperating with complementary teeth on the adjacent flange of the ring to hold the ring against circumferential movement.

As is indicated in the drawings, the ring sections may be hollow and provided with air passages and apertures.

The terminology used in the specification is for the purpose of description and not of limitation, the scope of the invention being indicated in the claim.

I claim:

A rotary cylinder riding ring comprising a plurality of arcuate sections, the sections having their adjacent ends secured together by respectively complementary hooks, each of said hooks including a shank portion which is an extension of the ring section and a head at the outer end of the shank, said head including a detent surface which lies at substantially a right angle with respect to the circumferential center line of the ring, securing means extending through the engaged hooks in a direction transversely of

the ring, and annular retaining means adapted to be secured to the cylinder and abutting both side walls of the ring so as to limit axial displacement of the ring with respect to the cylinder, the abutting surfaces of said retainer means and the ring side walls being smooth and planar so as to allow the ring to rotate freely with respect to the cylinder.
